WEATHER STRIP

Alfred M. Lane, St. Louis County, Mo., assignor to
 Monarch Metal Weatherstrip Corporation, St.
 Louis, Mo., a corporation of Missouri

Application November 4, 1935, Serial No. 48,167

18 Claims. (Cl. 20—69)

This invention relates to weatherstrips, particularly metal weather strips for windows equipped with sliding sashes. It has for its principal objects to provide an efficient and durable weatherstrip of simple and economical construction which can be readily applied to the window without material alteration thereof; which will prevent rattling of the sash in the frame; which will automatically accommodate itself to shrinking and swelling of the sash and frame and, at the same time, maintain a weatherproof joint therebetween and insure an easy movement of the sash; which will permit removal of the sash from the frame without removing the sash strip from the sash or the frame strip from the frame; and which will permit the frame strip to be mounted in and dismounted from the frame with the parting bead as a unit.

The invention consists in the weatherstrip and in the construction, combinations and arrangements of parts hereinafter described and claimed.

In the accompanying drawing, which forms part of this specification and wherein like symbols refer to like parts wherever they occur,

Fig. 1 is a fragmentary horizontal section through one side of the frame and the adjacent portion of the sash of a double hung window equipped with a metal weatherstrip embodying my invention,

Fig. 2 is a similar section, showing the weatherstrip on an enlarged scale,

Fig. 3 is a view looking at the lower portion of the parting bead side of the sash strip; and

Fig. 4 is a horizontal cross-section similar to Fig. 2 showing a metal weatherstrip of modified form.

Figs. 1, 2, and 3 of the accompanying drawing show the invention in connection with a double hung window construction comprising a window frame including a pulley stile or jamb A, a stop B, and a parting strip or stop C mounted in a groove C' provided therefore in said pulley stile or jamb, all arranged to form a vertical slideway for a closure member or sash D. The joint between the vertical meeting edges of the pulley stile A and the sash D of said window is rendered weatherproof and dustproof by means of a weatherstrip comprising cooperating strips E and F mounted on the parting strip C and the sash D, respectively.

The frame or stile member E of the weatherstrip is made of a strip of resilient metal that is bent or folded lengthwise along one line to form a side marginal flange 1, which has a hemmed free marginal edge 2, a portion 3 disposed sub-

stantially at right angles to said flange, an outstanding longitudinal rib 4 on said flange where it joins the portion 3, and a resilient hollow bead portion 5 that forms a connecting hinge between the portion 3 and a portion 6 that extends in the direction of the marginal flange 1 at a diverging or oblique angle to the portion 3 and then parallel therewith to a point short of the flange 1 where it joins the other side marginal flange 7, which is doubled back over the portion 6 to form a groove 8 and terminates in a hemmed free marginal edge. The sash member F of the weatherstrip is also made of a strip of resilient metal that is longitudinally bent or folded to form a portion 9, a flange 10 at one margin of the portion 9 that is provided with a hemmed free marginal edge 11 and is disposed substantially parallel with but spaced from the portion 9 to form a groove 12 on one side thereof, a portion 13 extending from the other margin of the portion 9 substantially at right angles thereto on the other side thereof, and a resilient flange 14 extending from the free margin of the portion 13 on the side thereof remote from the portion 9 to a point beyond the other margin of the portion 13 where it terminates in a free marginal portion 15 that is curved in the direction of the groove 12.

The frame member E is mounted in the frame of the window with its marginal flange 1 alongside of the sash opposing face of the parting strip C, with its portion 3 alongside of the sash opposing face of the pulley stile A and with its groove 8 disposed alongside of the stile opposing edge of the sash D and opening toward the side of said sash remote from said parting strip. The frame strip E is secured to the parting strip C along the hemmed edge 2 of its flange 1 by tacks or other suitable fasteners 16; and the rib 4 on the opposite edge of said flange fits in a longitudinal groove 17 provided therefor in the sash opposing face of the parting strip C in the plane of the sash opposing face of said pulley stile A. The sash strip F has its portion 13 disposed alongside of the parting bead opposing face of the sash D and secured thereto along the margin remote from the portion 9 by tacks or other suitable fasteners 18; and the portion 9 of said strip is disposed alongside of the stile opposing face of said sash with the hemmed marginal flange 10, which forms one wall of the groove 12, fitting within the groove 8 in the frame strip E. When the frame and sash strips are thus engaged, the curved free marginal edge 15 of the marginal flange 14 of the sash strip resiliently engages the

frame strip along the line where it is bent to form the groove 8.

At the lower end of the sash strip F, the resilient frame strip engaging flange 14 thereof has its free marginal portion cut away, as at 19 at its lower end so as to permit said flange to clear the grooved lower end of the frame strip when the sash is raised to its full height, thereby permitting engagement and disengagement of the 10 interlocked ends of the two strips in a horizontal direction instead of a longitudinal direction. As shown in Fig. 3, the edge of the sash strip flange 14 is cut at an oblique angle so as to guide the sash strip into engagement with the frame strip. 15 The foregoing weatherstrip has numerous advantages. The marginal flange 10 which forms one wall of the groove 12 in the sash strip F, fits within the groove 8 in the frame strip E and the marginal flange 7, which forms one wall of 20 the frame strip groove, fits within the sash strip groove thus giving a double, slidably interlocked engagement between the two strips. The marginal flange 14 of the sash strip E bears resiliently against the frame strip where it is bent to 25 form the sash strip receiving groove 8 and thus holds the two strips in slidably interlocked engagement and resists movement of the sash between the stop B and parting bead or stop C, thereby preventing rattling of the sash in the 30 frame. In the event the sash warps, the portions 9 and 13 of the sash strip will conform to the warp of the sash and the flange 14 of said sash member will remain straight and in full line contact with the frame strip and thus maintain 35 the two strips in engagement. The curved edge 15 of the flange 14 of the sash strip also tends to pull the frame strip away from the frame as the sash shrinks, thereby relieving the strain on the interlocking portions of the strips that is liable to cause leakage of air therebetween. The beveling off of the lower end of the resilient flange 14 of the sash strips permits the two strips to be quickly and easily engaged and disengaged in the raised position of the sash without removing 40 the sash strip from the sash or the frame strip from the parting bead; and the mounting of the frame strip on the parting bead permits these two members to be attached to and removed from the frame as a unit. The rib and groove engagement between the frame strip and parting bead tends to prevent passage of air around the parting bead; and, if the sash shrinkage is enough to pull the hollow bead portion 5 of the frame strip away from the pulley stile, the portion 3 carrying said bead will bend at the rib 4 and swing the grooved sash strip engaging portion thereof in the direction of the parting strip, thus forcing the sash in the direction of said parting strip and preventing increased clearance 45 therebetween.

In the modified construction shown in Fig. 3, the weatherstrip comprises a single frame strip E' that is bent to form a marginal flange 1a having a hemmed margin 2a secured by tacks 16a to the sash opposing face of the parting strip C and a ribbed margin 4a that fits in the groove 17 in said face of said parting strip, and a portion 3a that extends from said ribbed margin 4a to the marginal flange 1a alongside of the pulley stile A and is provided with a hollow bead 5a that forms a hinge connection between said portion and the other marginal or sealing flange 7a of said strip that extends in the direction of the marginal flange 1a at a diverging oblique angle to the portion 3a and terminates at its free

margin in a reversely inclined hemmed portion 7b that bears resiliently against the stile opposing face of the sash D. This construction forms a simple and efficient one-piece weatherstrip that prevents passage of air around the parting bead groove and can be removed and properly replaced with the parting bead without removing the securing nails for said strip and damaging the latter. 5

Obviously, the invention is not limited to use 10 with the window construction shown and described.

What I claim is:

1. The combination with a frame member having a closure member and a removable stop therefor, of a weatherstrip interposed between the meeting edges of said members, said weatherstrip being mounted on said stop for insertion and removal therewith as a unit, said weatherstrip having a longitudinal rib thereon seated in 20 a longitudinal groove provided therefor in the closure opposing face of said stop. 15

2. The combination with a frame member having a closure member and a removable stop therefor, of a weatherstrip interposed between the meeting edges of said members, said weatherstrip being mounted on said stop for insertion and removal therewith as a unit, said weatherstrip having a longitudinal rib thereon seated in a longitudinal groove provided therefor in the closure opposing face of said stop, said groove being located substantially in the plane of the 30 closure opposing face of said frame. 30

3. The combination with a frame member having a closure member and a removable stop therefor, of a weatherstrip interposed between the meeting edges of said members, said weatherstrip having a portion secured to the closure opposing face of said stop, whereby said weatherstrip is adapted to be inserted in and removed 40 from said frame with said stop as a unit, and a portion extending between said frame and said closure and sealing the space therebetween. 35

4. The combination with a frame member having a closure member and a removable stop therefor, of a weatherstrip interposed between the meeting edges of said members, said weatherstrip having a portion secured to the closure opposing face of said stop, whereby said weatherstrip is adapted to be inserted in and removed 45 from said frame with said stop as a unit, and a portion extending between said frame and closure and having a rebent sealing flange adapted to yieldably engage the frame opposing face of said closure. 50

5. The combination with a window frame having a sash slidable therein between a stop and a removable parting strip, of a weatherstrip interposed between the meeting edges of said frame and said sash and secured to said parting strip 60 only, said weatherstrip having a longitudinal rib thereon seated in a longitudinal groove provided therefor in the sash opposing face of said parting strip. 55

6. The combination with a window frame having a sash slidable therein between a stop and a removable parting strip, of a weatherstrip interposed between the meeting edges of said frame and said sash and secured to said parting strip only, said weatherstrip having a longitudinal rib theron seated in a longitudinal groove provided therefor in the sash opposing face of said parting strip close to the sash opposing face of said frame and a portion extending from said rib be- 70

tween said frame and said sash to seal the space therebetween.

7. The combination with a window frame having a sash slideable therein between a stop and a removable parting strip, of a weatherstrip interposed between the meeting edges of said frame and said sash and secured to said parting strip only, said weatherstrip having a longitudinal rib thereon seated in a longitudinal groove provided therefor in the sash opposing face of said parting strip close to the sash opposing face of said frame, a portion extending from said rib between said frame and said sash and a sealing flange doubled back upon said portion and connected thereto by a hollow bead.
- 5.
- 10.
- 15.

15. The combination with a window frame having a sash slideable therein between a stop and a removable parting strip, of a weatherstrip interposed between the meeting edges of said frame and said sash and secured to said parting strip only, said weatherstrip having a longitudinal rib thereon seated in a longitudinal groove provided therefor in the sash opposing face of said parting strip close to the sash opposing face of said frame, a portion extending from said rib between said frame and said sash and a sealing flange doubled back upon said portion and connected thereto by a hollow bead, said sealing flange bearing resiliently against said sash.

30 9. The combination with a window frame having a sash slidable between a stop and a parting strip, of a weatherstrip interposed between said frame and said sash and comprising a single frame strip and a single sash strip, the frame strip comprising a flange secured directly to the sash opposing face of said parting strip only and a portion disposed alongside of said frame opposite the frame opposing edge of said sash, and the sash strip comprising a portion secured directly to the parting bead opposing face of said sash and a portion disposed alongside of the frame opposing edge of said sash, the portion of the frame strip disposed alongside of said frame being doubled back toward said parting strip and terminating in a doubled-back flange forming a groove opening away from the sash opposing side of said parting strip and the portion of the sash strip disposed alongside of the frame opposing edge of said sash having a doubled

50 opposing edge of said sash having a doubled-back flange forming a groove opening toward the sash opposing side of said parting strip, the doubled-back groove forming flange of said frame strip fitting in the groove in said sash strip and the doubled-back groove forming flange of said sash strip fitting in the groove in said frame strip.

55 10. The combination with a window frame having a sash slideable between a stop and a parting

60 a self adhesive between a stop and a parting strip, of a weatherstrip interposed between said frame and said sash and comprising cooperating frame and sash strips, the frame strip comprising

60 a flange secured to the sash opposing face of said parting strip and a portion disposed alongside of said frame opposite the frame opposing edge of

65 said frame opposite the frame opposing edge of said sash, and the sash strip comprising a portion secured to the parting bead opposing face of said sash and a portion disposed clear of

of said sash and a portion disposed alongside of the frame opposing edge of said sash, the portion of the frame strip disposed alongside of said frame having a doubled back surface.

frame having a doubled-back flange forming a groove opening away from said parting strip and the portion of the sash strip disposed alongside of the frame.

of the frame opposing edge of said sash having a doubled-back flange forming a groove opening toward said parting strip, the doubled-back groove forming flange of said frame strip fitting

in the groove in said sash strip and the doubled-back groove forming flange of said sash strip fitting in the groove in said frame strip, the parting bead opposing portion of said sash strip having a doubled-back portion forming a flange adapted to bear resiliently against the frame strip where it is doubled-back to form the groove therein.

11. The combination with a window frame having a sash slideable between a stop and a parting strip, of a weatherstrip interposed between said frame and said sash and comprising cooperating frame and sash strips, the frame strip comprising a flange secured to the sash opposing face of said parting strip, a rib fitting in a groove in said face and a portion extending from said rib alongside of said frame opposite the frame opposing edge of said sash, and the sash strip comprising a portion secured to the parting bead opposing face of said sash and a portion disposed alongside of the frame opposing edge of said sash, the portion of the frame strip disposed alongside of said frame having a doubled-back flange forming a groove opening away from said parting strip and the portion of the sash strip disposed alongside of the frame opposing edge of said sash having a doubled-back flange forming a groove opening toward said parting strip, the doubled-back groove forming flange of said frame strip fitting in the groove in said sash strip and the doubled-back groove forming flange of said sash strip fitting in the groove in said frame strip, the parting bead opposing portion of said sash strip having a doubled-back portion forming a flange having a curved margin adapted to bear resiliently against the frame strip where it is doubled-back to form the groove therein.

12. A weatherstrip having a marginal flange adapted to be secured to a supporting member and provided along one edge with an outstanding rib, a portion extending from said edge of said marginal flange at an angle thereto on the side thereof opposite said rib, a portion doubled back over said first mentioned portion in the direction of said marginal flange, and a marginal flange doubled back over said second mentioned portion and forming a groove opening away from said first mentioned marginal flange.

13. A weatherstrip for windows having sliding sashes, said weatherstrip comprising a portion adapted to be secured to a sash, an angularly disposed portion at one edge of said first mentioned portion, a marginal flange doubled back upon said angularly disposed portion to form a groove opening in the direction of said first mentioned portion, and a marginal flange doubled back over said first mentioned portion from the other edge thereof and extending across the free edge of said first mentioned doubled back marginal flange. 50 55

14. A weatherstrip for windows having sliding sashes, said weatherstrip comprising a portion adapted to be secured to a sash, an angularly disposed portion at one edge of said first mentioned portion, a marginal flange doubled back upon said angularly disposed portion to form a groove opening in the direction of said first mentioned portion, and a marginal flange doubled back over said first mentioned portion from the other edge thereof and extending across the free edge of said first mentioned doubled back marginal flange, said second mentioned marginal flange being cut away at one end opposite said free edge of said first mentioned marginal flange. 60 65 70

15. A weatherstrip for windows having sliding 75

sashes, said weatherstrip comprising a frame strip having a marginal flange adapted to be secured along one edge to the window frame and having an outstanding rib at its opposite edge, a portion extending at an angle to said flange adjacent to the ribbed edge thereof, a portion doubled back on the angularly disposed portion and spaced therefrom and a marginal flange doubled back upon said doubled-back portion to 5 form a groove opening away from said first mentioned flange, and a sash strip having a portion adapted to be secured along one edge to a sash and provided along its opposite edge with an angularly disposed portion, and a marginal flange doubled back upon said angularly disposed portion to 10 form a groove opening in the direction of said first mentioned portion of said sash strip, the doubled-back marginal flange of said sash strip being adapted to fit in the groove of said 15 frame strip and the doubled-back marginal flange of said frame strip being adapted to fit in the groove of said sash strip.

16. A weatherstrip for windows having sliding sashes, said weatherstrip comprising a frame strip having a marginal flange adapted to be secured along one edge to the window frame and having an outstanding rib at its opposite edge, a portion extending at an angle to said flange adjacent to the ribbed edge thereof, a portion 20 doubled back on the angularly disposed portion and spaced therefrom and a marginal flange doubled back upon said doubled-back portion to form a groove opening away from said first mentioned flange, and a sash strip having a portion 25 adapted to be secured along one edge to a sash and provided along its opposite edge with an angularly disposed portion, and a marginal flange doubled back upon said angularly disposed portion to form a groove opening in the direction of said first mentioned portion of said sash strip, the doubled-back marginal flange of said sash strip being adapted to fit in the groove of said 30 frame strip and the doubled-back marginal flange of said frame strip being adapted to fit in the groove of said sash strip, said sash strip having a marginal flange doubled back upon said first mentioned portion thereof and terminating in a free edge portion adapted to bear resiliently against said frame strip where its marginal flange is doubled back to form the groove 35 therein, said last mentioned doubled-back marginal flange of said sash strip having its frame strip engaging portion cut away at one end thereof.

17. A weatherstrip for windows having sliding sashes, said weatherstrip comprising a frame strip having a marginal flange adapted to be secured along one edge to the window frame and having an outstanding rib at its opposite edge, a portion 40 extending at an angle to said flange adjacent to

the ribbed edge thereof, a portion doubled back upon the angularly disposed portion and spaced therefrom and a marginal flange doubled back upon said doubled-back portion to form a groove opening away from said first mentioned flange, 5 and a sash strip having a portion adapted to be secured along one edge to a sash and provided along its opposite edge with an angularly disposed portion, and a marginal flange doubled back upon said angularly disposed portion to form a groove 10 opening in the direction of said first mentioned portion of said sash strip, the doubled-back marginal flange of said sash strip being adapted to fit in the groove of said frame strip and the doubled-back marginal flange of said frame strip being 15 adapted to fit in the groove of said sash strip, said sash strip having a marginal flange doubled back upon said first mentioned portion thereof and terminating in a free edge portion adapted to bear resiliently against said frame strip where its 20 marginal flange is doubled back to form the groove therein, said last mentioned doubled-back marginal flange of said sash strip having its frame strip engaging portion cut away at one end thereof.

18. The combination with a window frame having a sash slidable between a stop and a parting strip, of a weatherstrip interposed between said frame and said sash and comprising cooperating frame and sash strips, the frame strip comprising 30 a flange secured directly to the sash opposing face of said parting strip and a portion disposed alongside of said frame opposite the frame opposing edge of said sash, and the sash strip comprising a portion secured directly to the parting 35 bead opposing face of said sash and a portion disposed alongside of the frame opposing edge of said sash, the portion of the frame strip disposed alongside of said frame having a doubled-back flange forming a groove opening away from the 40 sash opposing side of said parting strip and the portion of the sash strip disposed alongside of the frame opposing edge of said sash having a doubled-back flange forming a groove opening toward the sash opposing side of said parting 45 strip, the doubled-back groove forming flange of said frame strip fitting in the groove in said sash strip and the doubled-back groove forming flange of said sash strip fitting in the groove in said frame strip, the parting strip engaging flange 50 of said frame strip being provided adjacent to the sash opposing face of said frame with a longitudinal rib that seats in a groove provided therefor in the sash opposing face of said parting strip.

ALFRED M. LANE. 55
